MOTOR CASING FOR A PORTABLE RUBBING MACHINE

Roy J. Champayne, Rockford, Ill.

Application December 8, 1949, Serial No. 6,500

Term of patent 14 years

(Cl. D9—2)

To all whom it may concern:

Be it known that I, Roy J. Champayne, a citizen of the United States, residing at Rockford, in the county of Winnebago and State of Illinois, have invented a new, original, and ornamental Design for a Motor Casing for a Portable Rubbing Machine, of which the following is a specification, reference being had to the accompanying drawings, forming a part thereof.

In the drawings:

Figure 1 is a side elevational view of a motor casing for a portable rubbing machine showing my new design.

Fig. 2 is a plan view.

Fig. 3 is an end elevational view.

I claim:

The ornamental design for a motor casing for a portable rubbing machine, substantially as shown.

ROY J. CHAMPAYNE.
